W. H. SMYTH

TRACKLAYER CHAIN

Filed March 28, 1922

UNITED STATES PATENT OFFICE.

WILLIAM H. SMYTH, OF BERKELEY, CALIFORNIA.

TRACKLAYER CHAIN.

Application filed March 28, 1922. Serial No. 547,383.

My invention relates to chains for self-laying-track vehicles. It has for its main object to provide a cheap and effective track-chain adapted to permit of high speed in self-laying-track motor vehicles. And to this end to provide a strong light-weight all-around anti-friction track-chain made up of unmachined cast parts, pressed metal, and stock material, hence cheap to construct; and so devised as to be adapted to be readily assembled or renewed in place of use without the employment of tools.

A typical expression of my invention is shown in the accompanying drawing, where-

15 in:

Fig. 1 shows a side elevation of links in an endless track chain for tracklayer tractors, partly broken away on line $x-x$ of Fig. 2, and with some parts removed for 20 clearness of illustration.

Fig. 2 shows a plan view partly in section with parts removed as in Fig. 1.

Fig. 3 shows a transverse section on line y of Fig. 1.

25 Referring to the drawing A—A¹ are chain links. In the form shown they are right- and left-handed, though this is not essential. Otherwise they are of substantially similar construction.

30 The link A is provided at one end with a shell a , the other end of the link being provided with an inwardly offset hinge boss a^1 of like diameter as the shell and adapted to co-act with the shell of a succeeding link as 35 a closure wall a^2 for one end of its co-acting shell. The other end of the shell is also normally closed by means which will later be described. In the hinge boss a^1 is a semi-circular ended recess a^3 one end of which is 40 provided with a hole a^4 through the closure wall a^2 Fig. 2.

The inner part of link A is preferably ribbed to form a load-bearing track rail head a^5 . In the lower side of the link are 45 two inwardly extending recesses a^6 — a^6 and on either side of the recesses a^6 the metal of the link may project outwardly below the normal lower surface of the link, as shown at a^7 in Figs. 1 and 3.

50 A loosely rollable sprocket-abutment pin B projects into the hole a^4 , and extends across the space between links A—A¹ into hole a^4 of link A¹ its length being such that

it is somewhat shorter than the width of the chain, to permit of slight endwise play. 55

C is a short roller seated in the recess a^3 and it extends into shell a . The roller is preferably of like diameter to pin B with which it is in rolling contact, shown clearly in the section side of Fig. 2. The pins B 60 and rollers C, for lightness and air-cooling, may be made tubular as shown at the right-hand end of Fig. 1. In the shell a , above and below the rollers B and C are segments D—D¹ loosely fitting between their peripheries and the inner circumferential wall of the enclosing shell. The metal of the link forms a partial closure for the outer side of the shell; and to complete the closure there is provided a slideable plate E flush with the 70 outer metal of the link.

Upon the pin B, between the links A—A¹ is an anti-friction roller F of a diameter suitable to bring its periphery below the bearing surface of rail-head a^5 , thus forming 75 a two-duty trackway consisting of the rail-head surface for load-supporting truck wheels and a parallel sided guideway for antifriction roller co-action with any suitable chain-guide, substantially as this guide-rail trackway is shown in Fig. 3.

G are ground contact tread-shoes of suitable dimensions, preferably formed of pressed metal, bent upward at their outer edges. Below the normal bottom surface of 85 the shoe are integral pressed sheet metal cleats g which extend laterally across the shoe for traction purposes. Cleats g are positioned to correspond to the projections a^7 — a^7 of the links A—A¹ and to conform in 90 cross-sectional shape thereto, as clearly shown in Fig. 1 at a^7 — a^7 . Corresponding in position and shape to the recesses a^6 — a^6 the metal of shoe G is reversely pressed on the line of the cleats. This reverse pressed 95 metal on a line with the cleat constitutes an inwardly projecting loop g^1 of the shoe metal which fits snugly into its corresponding recess a^6 ; this is clearly indicated in the dotted lines at g^1 of Fig. 1 and shown at g^1 , 100 sectioned, in Fig. 3. Holding pins g^2 are driven through holes in the side metal of the link so positioned as to pass through the loops g^1 — g^1 and thus secure the tread-shoes to the links. 105

The described construction lends itself to

many desirable modifications to meet various conditions of operation, manufacture, and use. Some of these are indicated in the figures of the drawings. For example, in 5 the first link of Fig. 2, the projections a^7 — a^7 with the associated metal may extend outwardly, and inwardly across the links A — A^1 integral therewith and thus form a connecting member for the laterally adjacent links, 10 and also form a solid filler for the pressed metal cleats. In the links as shown in Fig. 2, the shoe itself maintains the operative relation of A to A^1 and the cleat filler is integral with the metal of each track link, 15 serving principally as registering and shoe holding means. These cleat fillers with their associated metal may extend half-way between the links and serve as convenient lateral abutments through which the pins g^2 20 would then act as effective dowel-pins.

The assembling and operation of a track-chain constructed as above set forth are as follows:—

Links A — A^1 , are cast separate. They are 25 then placed on the shoe; the loops of the shoe and coacting recesses ensure their proper positioning and the dowels g^2 give a secure but easily disconnected attachment. The integral cleats serve the function of 30 transverse ribs which with the bent up edges of the shoes together constitute the shoe a light but strong and rigid base connection for the thus positioned and attached links. This constitutes a track-chain unit.

35 Two of the thus assembled units are now positioned with the hinge bosses inserted between the corresponding shells of the other unit. The rollers B — C , which may be of commercial round stock or commercial piping, and the segments also may be of suitable ("half-round") stock, for these parts are loose fitting, are now placed in position through the aperture in the shell, and the sliding closure moved into place. 40 This simple assembly process is repeated till the desired length of chain is made.

50 In operation the links flex on the line of contact of the rollers B — C with anti-friction rolling action. The rollers F serve not only as anti-friction abutments for any co-acting driving or driven sprocket-wheel, but also serve as rollers to diminish friction of the chain when passing around whatever character of idler-wheel or idler guide the 55 chain may co-act with in operative association.

It is evident that many modifications may be made without departing from my invention, I therefore desire to claim the invention broadly without other limitations than the claims which follow may rightfully import.

I claim:—

1. A track chain link comprising a tread

shoe, a load bearing track-rail thereon provided with a normally closed shell, a similar track-rail laterally spaced apart therefrom to form a two-rail track, connecting means adapted to maintain the operative relation of the rails, a rollable hinge-pin across the intervening space one of its ends seated in each of the rail shell members, a roller in each of the shells in peripheral rolling contact with its respective end of the pin and a roller journaled on the pin between the rails. 75

2. A track chain made up of a longitudinal series of tread shoes bearing inside and outside overlapping hinge link members spaced apart to form a two-rail track, each outside overlapping member being provided with a shell having an outside dirt-excluding closure, a loose rollable pin across the intervening space and extending through the inside link member into the shell uniting adjacent overlapping links in hinge association, 80 antifriction roller-bearing means in each outside shell in antifriction co-operation with the pin and a freely rotatable roller journaled on the pin between the rails. 85

3. In a tracklayer chain having tracks laterally spaced apart to form a two-rail track, a freely rotatable hinge-pin across the intervening space with antifriction roller-bearings at its ends. 90

4. In a tracklayer chain having tracks laterally spaced apart to form a two-rail track, a freely rotatable hinge-pin across the intervening space with antifriction roller-bearings at each of its ends and a roller on the pin between the tracks. 95

5. In a tracklayer chain having tracks spaced apart to form a two-rail track, a freely rotatable hinge-pin across the intervening space, an antifriction roller in peripheral contact with the pin at each of its ends and a roller on the pin between the tracks. 105

6. In a track-chain, links forming a two-rail track, a tread shoe therefor with integral loops of the shoe metal extending inwardly, 110 pockets in the links having lateral sides registering with the sides of the loops into which the loops project and pins traversing the links and loops to detachably secure the shoes to the links. 115

7. In a track-chain, links forming a two-rail track, a tread shoe uniting the links provided with laterally spaced apart integral loops of the shoe metal projecting inwardly into the material of the links and a pin traversing each loop and link to secure the links to the shoe and the links to each other. 120

8. A track chain link comprising a tread shoe, a detachable load bearing track-rail thereon, a similar track-rail laterally spaced apart therefrom to form a two-rail track, means adapted to register the rails on the 125

shoe in operative relation to each other consisting of loops of the shoe metal extending upward into the base of the rails and a locking pin traversing each rail and loop to detachably secure the link members to each other.

9. In a tracklayer chain having tracks

spaced apart to form a two-rail track, means to position the rails consisting of detachable tread shoes having loops extending upward into the base of the rails and pins traversing the rails and loops to lock the parts in operative relation. ¹⁰
